APPARATUS FOR DISCHARGING AND LOAD-
ING BURNISHING BARRELS

William R. Hartley, New Haven, Conn.

Application October 1, 1931, Serial No. 566,227

3 Claims. (Cl. 209—241)

My invention relates to an apparatus used in connection with barrels employed for burnishing metallic articles to receive the contents of such barrels and to recharge the barrels, and an object of my invention, among others, is to provide an apparatus of this kind by means of which the burnishing elements may be readily separated from the burnished articles and returned to the barrels for further burnishing operations, 10 the discharged burnished articles being deposited in receptacles that are conveniently removable from the apparatus.

One form of an apparatus embodying my invention and in the construction and use of which the objects herein set out, as well as others, may be attained is illustrated in the accompanying drawings, in which—

Figure 1 is a side view of my improved apparatus.

Figure 2 is a top view, with parts broken away to show construction, and parts being omitted for clearness.

Figure 3 is a detail sectional view on enlarged scale of a portion of the apparatus, the plane of section being approximately on the dotted line 3—3 of Figure 1.

Figure 4 is a top view of one corner of one of the releasing valves.

Figure 5 is a view in vertical section through the upper end of the hopper illustrating the operation of the buckets in delivering burnishing elements thereto.

In burnishing operations it is common practice at the present time to journal the burnishing barrels in standards of sufficient height to enable receptacles to be placed under the barrel to receive the contents thereof which are dumped into the receptacle. The burnishing elements having been separated from the burnished articles are returned to the barrel along with a new supply of articles to be burnished and together with a liquid compound which is employed in the burnishing operation, the barrel having been placed with its receiving opening approximately at the top for the purpose. This work of elevating the burnishing elements to the height required to place them in the barrel has been manually performed in different ways, all of which are very objectionable, owing to the labor and time required for the operation.

All of these objections are obviated in the use of my improved apparatus illustrated in the drawings herein, which apparatus comprises a frame composed of a base and a tower secured to 55 and rising from one end of the base. The base

frame is of rectangular shape and includes side rails 10 comprising opposite sides of the frame that may be of any desired shape and of any suitable material, and which are joined at their ends by end rails in any suitable manner. A pair of supporting wheels 11 are mounted in any suitable manner in the base frame for support of one end thereof, as that end opposite the tower, and the opposite or tower end is supported by a single wheel 12, which is mounted in a caster-like device. 60 This device includes a foot 13 which is forked to receive the journal of the wheel in a manner common to structures of this type, said foot being pivoted at 14 to a swivelling stud 15 rotatably mounted in a bearing in a bracket 16 secured to 65 the end of the base frame and as shown in Figure 1 of the drawings.

A hand lever 17 is rigidly secured to and extends from the foot 13 as a means for swinging it on its pivots and for moving the frame as a 70 whole by means of its supporting wheels just described. A catch 18 for said handle is secured to and projects from the frame 19 comprising the tower hereinbefore referred to.

A rest 20 for the end of the base frame opposite the wheels 11 is secured to the end of said frame and this rest may be a short length of channel iron fitted over the end rail of the base frame at the crosswise center thereof and the bracket 16 may be seated upon this rest, which 75 is provided on its bottom with ribs or studs to comprise gripping elements to hold the structure from movement when desired. When the handle 17 is swung downwardly this end of the frame will be raised and then supported on the wheel 12 and the handle may be then used to roll the frame to any desired location in a manner that will be readily understood and to guide it in such movements.

Brackets 21 are secured at intervals along the side rails 10 and a container 22, preferably of rectangular shape, is supported on these brackets. The upper edges of the sides of this container have anti-friction rollers 23 mounted thereon in any suitable manner, and a tray 24, 80 also preferably of rectangular shape, has flanges projecting laterally from its upper side edges which rest upon said rollers, the tray depending between the sides of the container at the upper part thereof. The bottom of the tray is a screen, 85 a portion only of the perforations being shown in Figure 2, such perforations being of a size to permit the burnishing elements to pass through but to retain the burnished articles.

As a means for facilitating the separation of 110

the burnishing elements and articles means are provided for shaking the trays this consisting of a link 25 removably attached at one end in any suitable manner to one end of the tray and 5 pivotally secured at its opposite end to a crank 26 supported in the tower frame and actuated through a belt 27 extending from a pulley secured to the spindle of a motor 28 also mounted on the tower frame.

10 The bottom of the container 22 slopes downwardly from each side to its lengthwise center along which it is provided with a slot or slots 29 through which the burnishing elements pass after rolling or sliding across the sloping bottom.

15 Gate valves 30 are slidably supported on a valve supporting plate 31 extending across the base frame from end to end and secured at its ends to the end rails of said base frame. The valves are operated as by means of bell crank levers 20 32 pivotally mounted on the plate 31 to which are attached actuating rods 33 extending to a suitable location in proximity to the tower, as shown in Figures 1 and 2. T-shaped guides 34 are secured to the plate 31 to guide the movements of the valves, the cross portions at the ends acting as stops for said valves to determine their closed positions, said guides being slightly thicker than the valves to provide space between the plate 31 and bottom of the container for free 25 sliding movements of the valves.

30 The apparatus includes means for transferring the burnishing elements from the container after separation from the burnished articles and for elevating them to such height that they will move by gravity to be again placed in the burnishing barrel or other receptacle that may be desired. This mechanism includes a conveyor embodying a pair of sprocket chains 35 having buckets 36 pivotally mounted between them, said 35 chains being supported on pairs of sprocket wheels 37, 38, 39 and 40, the pair 39 being mounted at the top of the tower and the other three pairs being mounted on the base frame. The sides and bottoms of the buckets are perforated 40 to permit the liquid that flows from the barrel 45 to drain off.

In order to close the space between the buckets and prevent the burnishing elements from passing through the conveyor when travelling horizontally underneath the container a lip 41 is 50 formed on the upper edge of one side of each bucket, said lips each being of a width to overlap the edge of the adjoining bucket and close the opening therebetween.

55 The plate 31 has slots 42 adapted to register with the slots 29 in the bottom of the container when the valves are in their opened positions. The sprocket wheels 38 are rotated by means of a chain extending from a sprocket on the motor 60 shaft as shown in Figure 1 of the drawings, the upper part of the conveyor underneath the container moving toward the tower and then upwardly.

65 Mounted between the sprockets 39 and around the shaft 43 supporting said sprockets is a hopper 44 to the lower end of which a chute 45 is connected that may be properly inclined as by rotation on the shaft 43 to cause flow of the burnishing elements into a burnishing barrel or other 70 receptacle. It is here explained that this apparatus when placed for use is located with the container 22 underneath said barrel and the delivery end of the chute in position for flow of the burnishing elements into the barrel. The location of the hopper within the loop formed at the

upper end of the conveyor is of particular advantage in that the buckets when discharging their loads are maintained for a period over the mouth of the hopper and a faster movement may be had than would be the case if the buckets were tipped in the opposite direction over a hopper located outside of the loops in the chains. Dumping of the buckets is effected by means of a roller 46 at the end of an arm projecting from the hopper, as shown in Figure 5, said roller being located in the path of movement of an upper edge of each bucket as it passes over the mouth of the hopper. Any suitable means may be employed for holding the chute 45 in such inclined position as it may be placed in when pivotally moved on its pivot.

80 The chains 35 may be supported in any well known manner to ensure close proximity of the mouths of the buckets to the under side of the plate 31. The pivotal mount of the buckets includes a sleeve 47 extending through each bucket and receiving in its opposite ends pivot studs 48, secured to and projecting from the links 49 of the chains and as shown in Figure 3 of the drawings, the pivots being so positioned on the buckets that the latter, by the action of gravity, will always be located with their mouths upward, and particularly after having been tipped from that position by the action of the roller 46. Any suitable stop may be employed to prevent each bucket 85 from tipping too far owing to the disposition of the greater weight on one side of the pivot, said stops therefore keeping the buckets with their open ends upward.

90 The container 22 is provided at that end opposite the tower with a removable screen 50 located between guides, as shown in Figure 2, said screen permitting outflow of such excessive amount of liquid as may accumulate in the container when the valves 30 are closed, as when the contents of 95 the barrel are being dumped into the container. The container is closed by an end 51 that is 100 removably held in place, said screen and said end being removable to permit the tray 24 to be slid out of the container.

105 In accordance with the provisions of the patent statutes I have described the principles of operation of my invention together with the device which I now consider to represent the best embodiment thereof; but I desire to have it understood that the device shown is only illustrative, 110 and that the invention may be carried out by other means and applied to uses other than those above set out.

115 I claim:

120 1. A discharging and loading apparatus including a frame, a container supported on said frame and having a sloping bottom terminating in an outlet slot, a valve to control movement of elements through said slot, a separating tray supported on said container, a chute projecting from said frame over said tray and spaced therefrom for the reception between said chute and tray of a container to be discharged and loaded, and a conveyor to carry elements from said container and deliver them to said chute.

125 2. A discharging and loading apparatus including a frame, a container supported on said frame and having a sloping bottom terminating in a plurality of slots, separately operable valves 130 for said slots to control movement of elements therethrough, a separating tray supported on said container, a chute projecting from said frame over said tray and spaced therefrom for the reception between said chute and tray of a 135

container to be discharged and loaded, and a conveyor to carry elements from said container and deliver them to said chute.

3. A discharging and loading apparatus including a frame, a container having a sloping bottom terminating in a slot supported on said frame, a valve plate underneath said container, a valve slidably mounted on said plate, a con-

veyor including buckets travelling underneath in proximity to said plate, a separating tray supported on said container, and a chute projecting from said frame over said tray and spaced therefrom for the reception between said chute and tray of a container to be discharged and loaded to receive elements from said conveyor.
